FLUSHING VALVE

Hugh J. Walker, Woburn, Mass.

Application May 28, 1935, Serial No. 23,827

2 Claims. (Cl. 137—104)

This invention relates to improvements in flushing apparatus for use in a water closet system, and more particularly to improvements in the means for controlling the flow of water into 5 and out of the flushing tank.

It is an object of my invention to provide flushing apparatus which eliminates the use of the usual ball check valve and which will operate without the noise and leakage that are objectionable characteristics of the ordinary flushing apparatus.

It is further an object of my invention to provide a flushing apparatus in which the discharge of the flushing water from the flush tank will be continuous without restriction in the flow until the flow is instantly and automatically stopped without the provision of any mechanical valve action.

A still further object of my invention is to 20 provide a flushing apparatus in which the flush tank will be refilled at continuous pressure without restriction of the flow until the tank is practically full, without the objectionable noise caused by a slow-closing refill valve.

Another object of my invention is the provision in a flushing apparatus of a single slidable valve that controls the flushing and refilling operation.

Further objects and advantages of my improvements will be more readily apparent from the following detailed description of a specific embodiment taken in connection with the attached drawings in which:

Fig. 1 is a plan view of the flush tank;

Fig. 2 is a sectional elevation of the flush tank;

Fig. 3 is a vertical section showing the valve mechanism in normal position;

Fig. 4 is a vertical section showing the valve mechanism in flushing position;

Fig. 5 is a vertical section of the valve mechanism in flushing position;

Fig. 6 is a detail section taken on the plane indicated 6—6 in Fig. 3;

Fig. 7 is a detail sectional view taken on the plane indicated 7—7 in Fig. 4; and,

Fig. 8 is a sectional plan view showing the connection between the float lifter arm and the valve.

The flush tank 10 is of the usual form and is 50 provided with a water intake pipe 12 and an outlet pipe 14 which discharges into the toilet bowl. Referring to Fig. 3, the intake pipe 12 is shown connected to a vertical extension pipe 16 within the flush tank, which constitutes a housing for a slidable sleeve valve 18. The pipe 16 has a

threaded, flanged coupling member 20 at its lower end, which seats upon a gasket 22, which in turn contacts with the end of the pipe 12. The coupling member 20 and gasket 22 are held in position by the coupling nut 24 which has a screw 5 threaded connection 26 with the pipe 12. The sleeve valve 18 has a solid head 28 at its lower end provided with a circular shoulder 30 which seats against the gasket 22 when the sleeve valve is in its normal closed position. It will be apparent that the water pressure in the intake pipe 12 normally acts upon the valve head 28 to hold the sleeve valve in its closed position.

The sleeve valve 18 has a hollow tubular chamber 32 which is placed in communication with the intake pipe 12 by the provision of notched passageways 34, which, when the valve is in the position shown in Fig. 4, permit flow of the water from the intake pipe into the chamber 32 of the sleeve valve. Between the head 28 of the valve sleeve and the passageways 34, openings 36 may be provided to permit a reduced flow of the water after the passageways 34 have been closed as the sleeve valve 18 is being moved towards its closed position; this reduction of the flow prevents pounding of the valve to its seated position. The extension pipe 16 is connected to piping 38 within the flush tank, which terminates in an upwardly directed discharge nozzle 40 as shown in Fig. 2. The piping 38 connects with the pipe 16 through a flattened valve port 42 and the sleeve valve 18 is provided with a notched port 44 which is brought into communication with the port 42 of the pipe 38 when the valve is in the lowered position shown in Fig. 4. The piping 38 30 may be provided with a vent 45 to eliminate the siphoning of all the water in the tank back to the water supply if the intake water pressure should fail. The outlet pipe 14 is connected to a 35 siphon tube 46 within the flush tank which has a U-shaped bend 48 above the normal water level within the flush tank and has a depending leg 50 which receives the nozzle 40, as clearly shown in Fig. 2.

It will be apparent that the leg 50 of the siphon tube is open at the lower end to permit flow of the water from the flush tank into the siphon tube. When the sleeve valve 18 is in the position shown in Fig. 4 the water from the intake pipe is permitted to discharge through the nozzle 40 and the upwardly directed jet of water produced in the leg 50 of the siphon tube starts the siphoning action, and the water in the flush tank will discharge through the outlet pipe 14 until the 50 water level has dropped below the open end of the 55

tube 50, whereupon the entrance of air will break the syphoning action.

A bracket 52 is connected by a sleeve 54 to the upper end of the extension pipe 16 and constitutes a pivotal support 56 for a lever arm 58, which is connected to a metal float 60 having a screw member 62 and a screw nut 64 at its upper end. The float 60 fits within a float chamber 66 which is fixed to the syphon tube 46 by the bracket 68. The chamber 66 has a flanged opening 70 in the bottom thereof, which loosely receives a guide stem 72 attached to the bottom of the float and provided with a valve portion 73.

The upper end of the sleeve valve 18 is closed as at 74 and provided with a pair of spaced arms 76, cross pins 78 and 80 extend between the arm 76, and constitute supports for rollers 82 and 84. The float lever arm 58 extends between the rollers 82 and 84. The bracket frame 32 also carries a pivot 86 on which is mounted a rockable lever arm 88, which has cam portions 90 and 92 for contacting with the roller 82. The rocker arm 88 is fixed by a screw 94 to a rod 96 which is bent, as shown in Fig. 1, to extend towards the front of the tank.

A flush lever 98 mounted upon the front of the tank 10 extends within the flush tank and is provided with a lateral arm 100. A stop pin 102 is employed to limit the normal position of the flush lever 98 and arm 100.

The intake extension pipe 16 is provided with an additional branch pipe connection 104 having a flattened port 106 and adapted to be brought into communication with a notched valve port 108 formed in the sleeve valve 18. The branch 104 communicates with the filling pipe 106, which extends downwardly in the flush tank somewhat below the open lower end of the syphon intake 50.

When the flush tank is full the valve mechanism will be in the closed position shown in Fig. 3. In order to flush the tank the lever 98 is manipulated to rock the arm 100 and raise the rod 96; this serves to turn the rocker arm 88 about its pivot 86 to bring it to the position shown in Fig. 4. During this movement the cam portion 92 will engage the roller 82 and force the sleeve valve 18 downwardly to the position shown in Fig. 4, thereby opening the sleeve valve against the force of the water pressure in the intake pipe. The rocker arm 88 will be held in this position by the engagement between the cam portion 90 and the roller 82, but the flushing lever 98 may return to its normal position when released.

As previously explained, when the sleeve valve 18 is in the position shown in Fig. 4 the intake water will flow from nozzle 40, thereby starting the syphon action through the syphon tube, and the tank will empty to flush the toilet bowl. The flushing flow will stop when the water level in the tank drops below the intake to the syphon tube, but the jet from the nozzle will continue and the reduced flow will tend to fill the toilet bowl. As the tank is being emptied the float 16 will slowly drop in chamber 66, since the water in the chamber 66 has a restricted flow through the passage 70. The lowering of the float will cause the arm 58 to engage the roller 84. The float will finally apply sufficient pressure to force the sleeve valve downwardly from the position shown in Fig. 4 to the position shown in Fig. 5; this will take place after the tank has been emptied and the syphoning action has been broken by the entrance of air into the syphon discharge tube. The movement of the sleeve valve 18 to the position shown in Fig. 5 will release the rocker arm 88 from engage-

ment with the roller 82 and permit a return of the rocker arm to its normal position, as shown in Fig. 5. At the same time the notched port 108 will be brought into communication with the port 106 and the intake water will flow through the filling pipe 110 to fill the flush tank. The water level will rise in the flush tank until it has reached a level above the open upper end of float chamber 66. It will be understood that the restricted passage 70 will be closed by valve 73 to prevent the flow of water into the chamber 66 to raise the float 60 until the water in the flush tank overflows into the upper end of the float chamber 66. The filling of the chamber 66 will release the pressure of the float upon the sleeve valve 18 and permit the closing of the sleeve valve 18 by the pressure of the intake water upon the head 28. As the sleeve valve is slowly moved towards its closed position the valve port 44 will again be brought into communication with the port 42 of the pipe 16 and intake water will flow through the piping and nozzle 40 to deliver a small amount of water into the toilet bowl, but without filling the pipe sufficiently to start a syphoning discharge from the tank. The flow of water through the discharge pipe will stop after the sleeve valve 18 is moved upwardly so as to stop the flow of the water through the nozzle 40. The sleeve valve 18 will then be brought to its normal closed position, and, as previously stated, the provision of small bleed openings such as 36 will allow the sleeve valve to come slowly to its seated position.

The flushing of the toilet bowl is rapid and thorough. The syphon flush can not be shut off by a defective ball valve as in the old system. The flush tank must empty before the flushing flow is automatically terminated. The filling of the toilet bowl after flushing is insured by the reduced flow through the discharge pipe of the intake water, which takes place in two steps, after the flushing flow and after filling of the flush tank just prior to closing of the intake valve. The flush tank is filled rapidly at continuous pressure from the intake and without the noise occasioned by a slow-closing refill valve.

Various modifications may be resorted to in the practice of my invention without departing from the spirit of my invention as expressed in the appended claims.

I claim:

1. In a flush tank, a water intake-pipe leading into the tank, said pipe having two delivery ports within the tank, one for initiating emptying of the tank and the other for filling the tank, a valve in said pipe for controlling delivery of water through said ports, manually operable means for moving the valve to one position to flush the tank, means operable when the tank is nearly empty for moving the valve further in the same direction to fill the tank and for holding the valve in said position until the tank is nearly full, said valve being closed by the water pressure when said last named means become inoperative by the admission of water to the tank, said valve consisting of a cylindrical sleeve slidable in the intake pipe and having two ports which are successively moved into operative position with relation to the respective delivery ports of said pipe, and the valve having a third port for the admission of water from the intake pipe in either of said operative positions.

2. In a flush tank, a water intake-pipe leading into the tank, said pipe having two delivery ports within the tank, one for initiating emptying of the tank and the other for filling the tank, a valve

in said pipe for controlling delivery of water through said ports, manually operable means for moving the valve to one position to flush the tank, means operable when the tank is nearly empty for moving the valve further in the same direction to fill the tank and for holding the valve in said position until the tank is nearly full, said valve being closed by the water pressure when said last named means become inoperative by the admission of water to the tank, said valve consist-

ing of a cylindrical sleeve slidable in the intake pipe and having two ports which are successively moved into operative position with relation to the respective delivery ports of said pipe, and the valve having a third port for the admission of water from the intake pipe in either of said operative positions, and having auxiliary openings permitting a reduced flow of water into the valve after said last named port has been closed. 5
